UNITED STATES PATENT OFFICE.

HENRY T. HOLLAND, OF NEW YORK, N. Y.

BRACKET.

No. 895,563.

Specification of Letters Patent.

Patented Aug. 11, 1908.

Application filed March 27, 1908. Serial No. 423,601.

To all whom it may concern:

Be it known that I, HENRY T. HOLLAND, a citizen of the United States, residing at New York, in the county of New York and State 5 of New York, have invented certain new and useful Improvements in Brackets, of which the following is a specification.

The present invention is a modification or improvement on the bracket shown and described in my U. S. Patent, No. 849,398, dated April 9, 1907.

The present invention has several novel features of construction as will more fully appear from the following description and the 15 accompanying drawings, in which,—

Figure 1 is a perspective view of the bracket. Fig. 2 is a perspective view of a modification.

The frame and brace of the bracket are 20 substantially the same as those shown in the above mentioned patent, having an upper V-shaped supporting piece bent to form two arms 6, and a brace bent to form a pair of arms 7 which are hooked as at 8, at their upper ends, through loops 9 formed by coils in the arms 6.

The arms 6 are attached to the wall or supporting structure by means of swinging plates 10 which are hinged to the arms by 30 means of tongues 11 which are looped around lateral extensions 12 at the inner ends of the arms, said extensions being bent forwardly at their ends to prevent the loops slipping off. The plates 10 are slotted as at 13 and 35 are also notched at their upper edges as indicated at 14, and attaching screws may be placed through the slots and the notches for the purpose of fastening the plates to the wall. The attachment for the brace is made 40 by means of a similar plate 10 with a tongue looped around the brace at the bend thereof.

The attaching plates may be swung in a vertical plane to any angle desired, and consequently the bracket can be attached to a 45 slanting wall in such manner that the arms of the bracket will nevertheless be horizontal. The slots 13 permit the bracket as a whole to be moved up or down without removing the screws, or without removing the bracket

from the wall. This is particularly advantageous in setting gas meters, because the meter can be moved up or down to fit the pipes, which is often necessary, owing to the variation in size of meters, some being larger or taller than others. Ordinarily, the attaching screws in the slots 13 will be sufficient to fasten the bracket to the wall, and it is not intended that screws will be placed in the notches 14 unless the wall is soft or it is otherwise necessary to use additional screws to hold the bracket in place.

The bracket can be folded into small space for transportation or storage, since all the attaching plates 10 can be folded down flat upon the wires of the bracket.

In the modified form shown in Fig. 2 the supporting piece of the bracket is made square, instead of V-shaped, and the wire is coiled to form a screw hole 16 at each corner, as well as screw holes 17 at the ends thereof. 65 70 Screws may be inserted through these holes for the purpose of fastening the bracket to the structure supported thereby. This will be useful where a shelf or other permanent structure is to be supported by the bracket. 75 Instead of the slots 13 in the plates 10 simple screw holes can be made, for the purpose of receiving the attaching screws.

I claim:

1. A bracket comprising spaced arms connected together at their outer ends and having lateral extensions at their inner ends, the extremities of the extensions being offset, a brace hinged to said arms, and attaching plates having tongues looped around said extensions, within the offsets, forming hinges.

2. A bracket comprising a piece of wire bent to form a pair of supporting arms with offsets at their inner ends and terminating in loops forming eyes for screws, a brace attached to the arms, and attaching devices connected to the offset and the brace.

In testimony whereof I affix my signature, in presence of two witnesses.

HENRY T. HOLLAND.
